LENS FOR HEADLIGHTS

James Thomas Hoal, Corpus Christi, Tex.

Application February 13, 1936, Serial No. 63,795

3 Claims. (Cl. 240—41.4)

The present invention relates to lenses to be used in connection with the conventional type of headlights upon automobiles and more particularly to a non-glare headlight lens having 5 amongst its principal objects the provision of a lens which may be readily substituted for the ordinary lens now used in headlights and when in use will have the appearance of the removed lens and yet cause a majority of the light rays 10 emitting therefrom to be directed out of the path of vision of approaching pedestrians and drivers.

A further object of the present invention is to provide a lens of the aforesaid character which will cause the light rays emitting from the upper 15 half of the headlight to be directed downwardly over the roadway over which the vehicle is travelling, while the beam of light from the lower half thereof will be composed of strong rays extending substantially parallel to the roadway and out of 20 the line of vision of the drivers of the approaching vehicles.

Still another object of the present invention is to provide a lens that will permit a beam of light to emit from only the lower half of the headlight, but said beam to combine the candlepower 25 of the beam of both halves of the headlight and at the same time, extend in a slightly downwardly slanting direction from a line perpendicular to the lens so as to be non-glaring to persons in a vehicle in the path of the beam.

Other objects of my invention will be in part obvious and in part pointed out hereinafter.

In order that the invention and its mode of operation may be readily understood by persons skilled in the art, I have in the accompanying 35 illustrative drawings and in the detailed following description based thereupon, set out an embodiment of the same.

In the drawings, wherein like characters of 40 reference designate corresponding parts throughout:

Figure 1 is a vertical sectional view of the lens embodying the invention when applied to a head lamp of a conventional type.

Figure 2 is a front elevation of the lens illustrated in Figure 1.

Figure 3 is a view similar to Figure 1 showing a slightly modified form of lens.

Figure 4 is a front elevation of the lens as illustrated in Figure 3, and

Figure 5 is another view similar to Figure 1 showing still another slightly modified form of the invention.

Referring now more particularly to the accompanying drawings wherein like and corre-

sponding parts are designated by similar reference characters throughout the several views, I have illustrated in Figure 1 a portion of an ordinary headlight used upon automobiles consisting of a reflector 6, an incandescent lamp 7 mounted in a socket 8 connected to the vertex of the reflector. The lens 1 embodying the present invention is to be substituted for the conventional headlight lens and mounted within the headlight in the usual manner. This lens is a 10 disc of transparent media which is divided into an upper section and a lower section. The lower section 2 has parallel faces throughout so that all light rays passing therethrough will have their emergent rays parallel to their incident rays. 15 However, above the center line 9 as is better illustrated in Figure 2, which is the point at which a ray perpendicular to the lens and passing on a horizontal plane through the center of the illuminating means would strike the lens, the inner face of the lens is composed of short arched reflecting polygonal surfaces 4 connected together by transparent surfaces 5, while the outer face 3 is a continuation of the lower outer face of the lens. These arcuate reflecting surfaces 4 extend at such an angle as to reflect all rays from the illuminating means 7 or the reflector 6 back to the reflector 6 in such a manner that the rays will be finally reflected from the lower half of the reflector 6 outwardly through the 20 lower portion 2 of the lens. The angle of the reflecting surfaces 4 is such as to regulate the angle of incidence at the point of final reflection so that the reflection will be in a downwardly slanting path as compared to a line passing from the center of the lamp to the center line 9 of the lens 1. The reflecting surfaces 4 are stepped in the manner as better illustrated in 25 Figure 1 so that such surfaces that are arranged adjacent the upper end of the lens will project inwardly at different angles from that of the reflecting surfaces located below said upper surfaces in order that a majority of the rays of light striking such surfaces will be reflected back and finally caused to pass through the lower transparent portion 2 of the lens. In this Figure 1 of the drawings, I have illustrated a possible pencil of rays caused by such reflection and also by arrows the possible refracted rays through the 30 transparent surfaces 5.

Due to the point at which line 9 is situated, all rays emitting from the incandescent lamp 7 pass through the lower portion 2 of the lens as downwardly extending rays.

The transparent surfaces 5 are naturally slanted because of their position between surfaces 4 so that all rays reflected by the upper portion of the reflector 6 that strike their surface are bent upon entering similar to the refraction effect produced by light entering one side of a prism. This bending causes the light beam to head in a downward manner until it strikes the outer face 3 of the lens 1 where upon emergence it is bent slightly upward as the change of velocity of the light wave in passing from the transparent media to the atmosphere causes the rays to bend upward as the upper rays of the beam strike the atmosphere first with the remainder of the rays emerging gradually along the line. The degree of slant of said transparent surface 5 is such that the emergent beam will slant downward. This is produced by the slant of the surface 5 being such that the bending of the incident ray is at such a downward angle as to greatly offset the upward bending tendency of the emergent ray.

With the present lens used in connection with a headlight, a beam of light is thrown directly downward with companion beams thrown outwardly but at a downward slant so that persons in vehicles in the path of the entire illumination are neither blinded nor forced to endure a glaring headlight and yet the headlight will have the appearance of a full circular lens of the conventional type whether the headlight be illuminated or not.

In order to render the surfaces 4 non-transparent and reflecting, they are covered or coated with silver thereby producing mirrored surfaces that will cause any rays of light striking the same to be reflected back against the reflector 6.

In Figures 3 and 4 of the drawings, I have illustrated a slightly modified form of the invention when applied to a concave-convex lens. In this form of lens the same is divided into a lower section and an upper section by means of a line 10 extending diametrically through the lens. The lower section 11 also consists of a transparent media having its outer faces extending parallel to one another. The inner face of the upper section is provided with a plurality of prismatic or polygonal reflecting surfaces 12 which are arranged in a stepped order as shown, whereby the distance between illuminating means and each reflecting surface 12 will be practically the same. These reflecting surfaces are preferably covered with silver in order to render the same non-transparent, whereas the surfaces 14 between these reflecting surfaces are transparent in order that the light rays may pass therethrough.

The modification as illustrated in Figure 5 shows the type of prismatic or polygonal reflecting surfaces 12 applied to a straight lens of the type as illustrated in Figure 1 of the drawings. However, in all forms of invention these reflecting surfaces are preferably of the arcuate design concentrically arranged in the manner as better illustrated in Figures 2 and 4 of the drawings and the width of these reflecting surfaces may be best determined by applying the same to various type head lamps according to the design of reflector 6 employed.

The arrow points and lines upon Figure 1 indicate the several illuminous pencils, but as the lamp 1 emits divergent rectilinear rays from all its points and in all directions, these pencil rays are of course only illustrative of a proposed theory upon which the lens functions. Likewise,

in Figures 3 and 5, the lenses shown will function according to the laws of reflection and refraction.

The reflector 6 may have a true parabolical curve and when the lens is applied to a conventional headlight having various designs of reflectors many pencil rays different from that herein set forth upon the drawings may be apparent, but nevertheless my lens when applied to a standard automobile headlight will cause an intense and far reaching light beam from the lower half thereof suitable for driving purposes and a greatly depressed beam of reduced intensity from the upper half thereof which will avoid the existence of the objectional "glare" or blinding effect upon the eyes of the driver or occupants of the approaching vehicle. The light distribution effected by the use of my lens will produce the customary light patterns having the usual horizontal beam spread, but with a vertical beam spread having its upper half depressed or of reduced intensity.

Manifestly, the construction herein shown is capable of considerable modification and such modifications as come within the scope of my claims, I consider within the spirit of my invention.

I claim:—

1. A headlight lens being equally divided into an upper and lower section, the opposed faces of said lower section being parallel, one face of said upper section extending contiguous with the outer face of said lower section, a plurality of prismatic projections of equal width formed integral with and extending from the inner face of said upper section, said prismatic projections having an upper and lower side, said lower side having a reflecting surface and each reflecting surface being of equal width, and said upper side having a transparent surface and each transparent surface increasing in width towards the upper end of the lens.

2. A headlight lens being equally divided into an upper and lower section, the opposed faces of said lower section being parallel, one face of said upper section extending contiguous with the outer face of said lower section, a plurality of prismatic projections of equal width formed integral with and extending from the inner face of said upper section, said prismatic projections having an upper and lower side, said lower side having a reflecting surface for reflecting all light rays striking said surface at a downward slant and increasing in width towards the upper end of said upper section, and said upper side having a transparent surface for casting all light rays striking said surface through said lens in a downward slant and said transparent surface increasing in width towards the top of said upper section.

3. A concavo-convex headlight lens comprising a body equally divided into an upper section and a lower section, the opposed faces of said lower section being concentric, projections formed integral with and extending from the inner face of said upper section, an arcuate reflecting surface formed with each projection and a transparent surface formed with each projection and arranged between said reflecting faces, the width of said reflecting surfaces and transparent surfaces gradually increasing towards the upper end of the lens and said projections each being of the same width.
